UNITED STATES PATENT OFFICE,

EDWARD G. WATKINS, OF GARDNER, MASSACHUSETTS.

DESIGN FOR CANE FABRIC.

SPECIFICATION forming part of Design No. 26,476, dated December 29, 1896.

Application filed November 27, 1896. Serial No. 613,707. Term of patent 7 years.

To all whom it may concern:

Be it known that I, EDWARD G. WATKINS, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design consists of the intersecting stripes *a* and *b* of contrasting color from the body of the fabric, the 15 stripes *a* being interrupted at regular intervals and appearing as rows of checks and the stripes *b* being interrupted to show the body of the fabric in the form of checks on each side between the stripes *a*.

20 *f* represents a piece of cane fabric bearing

my design, which consists of the stripes *a*, crossed by the stripes *b*, both of contrasting color from the body of the fabric *f*. The stripes *a* are made up of a series of squares *a'*, arranged in line and interrupted at intervals to show the body of the fabric *f*. The stripes or bars *b* are interrupted at regular intervals to show the body of the fabric in small squares on each side of the stripes *a*. 25

I claim—

30 The design for cane fabric, as herein shown and described.

In testimony whereof I have signed my name to this specification, in the presence of two subscribing witnesses, this 18th day of 35 November, A. D. 1896.

EDWARD G. WATKINS.
